UNITED STATES PATENT OFFICE.

GEORGE W. FIELD, OF EAST MILTON, MASSACHUSETTS, ASSIGNOR TO F. & F. SPECIALTY CO., OF BOSTON, MASSACHUSETTS, A CORPORATION OF MAINE.

CLOTHES-PIN.

1,113,109.

Specification of Letters Patent.

Patented Oct. 6, 1914.

Application filed November 14, 1913. Serial No. 800,990.

To all whom it may concern:

Be it known that I, GEORGE W. FIELD, a citizen of the United States, and a resident of East Milton, in the county of Norfolk 5 and State of Massachusetts, have invented certain new and useful Improvements in Clothes-Pins, of which the following is a specification.

This invention relates to spring clasps of 10 the type shown in Patents 380,013, granted March 27, 1888, to E. M. Ball, and 788,509, granted May 2, 1905, to E. W. and R. L. Ball, the device being particularly intended for use as "clothes-pins".

15 One of the objects of the invention is to provide an improved structure of clasp of the type referred to which will retain its operative condition without catching upon articles of wearing apparel, and being so 20 constructed that it will not twist relatively to the clothes-line, and having means whereby the locking action to prevent spreading of the jaws will be certain at any point.

25 To these ends the invention consists in the improved construction substantially as hereinafter described and claimed.

Of the accompanying drawings:—

Figure 1 is an elevation of my improved 30 clasp in its normal position or condition, when not in use; Fig. 2 is a similar view illustrating the device with the jaws open to their widest extent; Fig. 3 is a similar 35 view illustrating the clasp in use; Fig. 4 represents a section on line 4—4 of Fig. 3; Fig. 5 represents a section on line 5—5 of Fig. 3; Fig. 6 represents a section on line 6—6 of Fig. 1.

Similar reference characters indicate similar parts in all of the views.

The clasp consists of a single piece of 40 spring wire bent to form a bow 10, diverging arms 11, clasping jaws 12, and arms 13 leading from the jaw portions 12, said arms 45 being bent to form guide loops 14 (Fig. 4), the wire being then bent to form finger loops 15.

In general appearance the device as so far described resembles the structure of the 50 Ball patents above referred to.

To apply the clasp to fabric *b* hanging over a clothes-line or rope *a*, the user inserts a thumb and finger in the loops 5 and compresses them until the loops abut as in 55 Fig. 2, and then passing the diverging arms

11 down over the fabric and rope until the latter is between the jaws 12, after which the user releases the loops 15 and the spring action of the bow 10 causes the jaws to grip the fabric upon the rope. This operation 60 is similar to the operation of the Ball clothes-pin above referred to.

My improvements consist in providing means for rendering the locking action certain at any point, and in so constructing 65 the device that it will not twist or swing out of a plane substantially at a right angle to the direction of the clothes-line.

As shown in the drawings, the ends of the wire forming the loops 15 extend down 70 through the outer ends of the loops 14, the said ends being then bent outward, as indicated at 16. These ends are somewhat hook-shaped, as shown. This formation not only locates the ends of the wire in such position 75 that the loops 15 cannot be sprung out, and so that fabric cannot be caught upon the ends of the wire, but by the hooked engagement with the outer ends of the loops 14 the said loops are pulled upwardly from 80 the outer surface of the bow 10 when the clasp is being changed from the position shown in Fig. 1 to the position shown in Fig. 2. An especial function of the extensions 16 is that their inner tips 17 bear 85 against the outer surface of the bow 10 in a manner to bind thereon to resist any tendency of the jaws to spread. In other words, the hooked extensions 16 with their binding tips 17 serve to positively lock the clasp so that 90 it cannot possibly be opened by any force exerted between the jaws 12 or the arms 11. Referring especially to Fig. 3, it will be seen that any attempt to spread the jaws will be resisted by the arms 13, the pull upon such arms 13 95 simply binding the tips 17 tightly against the outer surface of the bow 10. Of course any such spreading tendency of the jaws would be transmitted through the arms 11 to the bow 10 and therefore would have a 100 tendency to spread the bow 10 in opposition to the pulling action of the arms 13. Therefore the ends of the loops 14 will cause only a tighter binding action between the portions 17 and 10 of the wire. The jaws 12 105 should of course so bind upon the rope or the fabric on the rope that there will be no tendency of the clasp to swing from the position indicated in Fig. 4, relatively to the rope. If the jaws were to contact with the 110

rope or the fabric, at such opposite sides of the latter as would have a tendency to cause the arms 13 to separate at their crossing point, then the spring of the bow 10 would 5 tend to cause the clasp to assume a position indicated by the line α in Fig. 4. This tendency of the clasp to swing is obviated by so bending the wires that the inner faces of the jaws 12 will grip practically opposite 10 portions of the material inclosed between them. By comparing Figs. 4. and 6 with Fig. 1, it will be seen that the wire, both above and below the gripping point of the jaws, is so bent laterally that the gripping 15 points of the jaws will engage the rope at points that will prevent any liability of the arms 13 spreading at their crossing point so as to permit the clasp to swing or twist to or toward the dotted line α in Fig. 4.

Having described my invention, I claim:

1. A clothes-pin formed of a single piece of wire and comprising a curved bow, grip-

ping jaws, guide loops inclosing the bow, and finger loops extending from the guide loops beyond the bow, the ends of the wire 25 extending into the guide loops outside of the bow.

2. A clothes-pin formed of a single piece of wire and comprising a curved bow, gripping jaws, guide loops inclosing the bow, 30 and finger loops extending from the guide loops beyond the bow, the ends of the wire extending into the guide loops outside of the bow, the inner sides of the finger loops being adapted to abut when the jaws are 35 open, to limit the maximum opening of the jaws.

In testimony whereof I have affixed my signature, in presence of two witnesses.

GEORGE W. FIELD.
